UNITED STATES PATENT OFFICE.

JOSEPH IRELAND, OF CLEVELAND, OHIO.

ORAL ANNUNCIATOR.

SPECIFICATION forming part of Letters Patent No. 269,860, dated January 2, 1883.

Application filed May 20, 1882. (No model.)

To all whom it may concern:

Be it known that I, JOSEPH IRELAND, of Cleveland, in the county of Cuyahoga and State of Ohio, have invented new and useful 5 Improvements in Oral Annunciators, of which the following is a specification.

This invention has for its object to provide a speaking-tube annunciator by which any one or more rooms in a building may be put into 10 instant communication with any other one or more rooms in the same building at the same time.

The invention consists of one speaking-tube leading from each of the rooms of a building 15 to some central point, and connected with an annunciator which comprises an exchange by which open communication may be quickly made, for the purpose of talking, between any one or more rooms with any other one or more 20 rooms, as above stated.

The construction and arrangement of the devices for producing said results will be fully understood from the subjoined description in detail, when considered in connection with the 25 accompanying drawings, in which—

Figure 1 is a front or face view of my annunciator and exchange device, having a portion of the front wall removed to expose the tubes for showing their connections. Fig. 2 30 is a vertical section of the same in line 2 2 of Fig. 1. Fig. 3 is a horizontal section of the same in line 3 3 of Fig. 1. Fig. 4 is a sectional view of one of the valves, which are located at the intersection of the perpendicular with 35 the horizontal tubes in the said exchange.

A is a box of suitable dimensions, which is to be attached to the wall of a room at convenient height, said room being located at some convenient central portion of a building.

40 Numbers 1, 2, 3, 4, and 5 represent speaking-tubes leading from a corresponding number of rooms. These tubes pass down through the box, and are provided with elbows at their lower ends, which pass out through the front 45 of the box and terminate with mouth-pieces. Said mouth-pieces are provided with covers for closing them, which are hinged at the lower side, the purpose of which covers is to give a signal to the attendant by their striking-bells B B, attached to the under side of the 50 box A, so located that the falling of said covers will touch them and cause them to ring.

The said covers are made to fall by the force of the wind blown through the pipes by the caller.

55

T T are horizontal tubes located close in rear of the perpendicular tubes, and are connected with the same by the valve-boxes D D at each of the crossings. The said boxes D D lie horizontally across the perpendicular tubes, 60 with their front ends resting against the inside of the front wall of the box A, as seen in Figs. 2 and 3. Within the said boxes D D are fitted slide-valves V V, operated by means of push-rods R R, working through holes in the front 65 wall of the box A, each rod having a knob, upon the faces of which are made numbers corresponding with the perpendicular tubes. Said valves V have perpendicular passages P through them, which, when the valves are 70 pushed in, open the ways through the said perpendicular tubes, but when drawn forward close or shut off the said ways. The rear ends of said valves V are formed with a curved bevel, v, which forms a communication between 75 the perpendicular to the horizontal tubes, as seen in section in upper part of Fig. 2, when the valve is drawn forward, and which also closes the opening to the perpendicular tube by the under surface of the valve covering 80 said opening. By means of these valves the passages in the tubes are made interchangeable, for the purpose hereinafter shown. One end of the horizontal tubes T T protrudes through the side of the box A, and there is 85 provided in the said ends a whistle, w, closed with a hinged cover, Z. The purpose of the whistle is for the person talking to give a signal, when done talking, to the attendant.

Another form of valve can be used, consisting of a hinged gate operated by a crank on the outside of the box A, arranged within the valve-box for changing the passages within said tubes; but the plan of slide-valve shown is preferable.

90

The operation of this device is as follows: Supposing occupant of room 1 desires to speak with occupant of room 4, No. 1 signals to the exchange by blowing through his tube. This causes cover of No. 1 mouth-piece in the exchange to fall and ring its bell. The attendant responds by voice. No. 1 then says he wants No. 4. The attendant then withdraws upper valves Nos. 1 and 4. This opens com- 95 rcc

munication between perpendicular tube 1 with 4 through the upper horizontal tube, T, so that the sound of No. 1's voice will pass to No. 4's room. Should No. 1 desire to speak the 5 same message to No. 5, he can do so at the same time by having No. 5's tube put in connection in the same manner. Now, supposing No. 2 desired to speak with No. 3 or No. 5 at the same time, he signals the attendant, who 10 immediately opens the communication by withdrawing the valves Nos. 2 and 3 in the second horizontal tube, thus putting two separate rooms in communication with two other separate rooms at the same time without one interfering with the other. When persons using 15 the device have done the attendant again pushes inward the valves, which shuts off the communication between the perpendicular and horizontal tubes, restoring the perpendicular tubes to their original condition—that is, open 20 to their mouth-pieces again. Then the device is ready for repeated use.

The object of the several counter-tubes TT is to provide for the sending of two or more 25 messages at one and the same time. If it be desired to send but one message at a time, but one cross or counter tube need be supplied. Otherwise, if more than one message is required to be sent, as in large buildings, then 30 there should be as many cross-tubes as are likely to be needed.

I aware that speaking-tubes have been provided with a valve connected to a bell by means of rods or levers, so that when air is blown through the tube the valve will oscillate, move the rods or levers, and cause the bell to strike. In my device the bell is so arranged that the cover of the speaking-tube, when blown open, will strike the bell and give 35 an alarm. Therefore

What I claim is—

1. In an annunciator, the combination, with a speaking-tube having a hinged cover hinged to the lower side of the mouth of the tube, of a bell placed below the mouth of the tube, 45 as described, so that when the cover is blown open the top will strike the bell.

2. In an annunciator, the combination, with a number of speaking-tubes placed parallel to each other within the annunciator, of a 50 number of secondary tubes placed transversely to the speaking tubes, and having air-passages joined to all the air-passages of said speaking-tubes, and of valves arranged within the tubing, substantially as described, and for the 55 purpose set forth.

3. A speaking-tube pipe crossing a second pipe, and connected together, substantially as shown, a sliding valve perforated to form the continuation of one pipe, and having an incline which serves as a switch to close one 60 pipe and open connection with the other, all combined and arranged substantially as described, and for the purpose set forth.

4. In an annunciator, the combination, with 65 a number of speaking-tubes placed parallel to each other, of a number of secondary tubes provided with signaling devices, and placed transversely to and connected with the speaking-tubes, substantially in the manner shown, 70 and of valves arranged within the tubing, substantially as described, and for the purpose set forth.

JOSEPH IRELAND.
